Harace Le Wilcox } inventor
West Meridian, Conn. 1866.

United States Patent Office.

HORACE C. WILCOX, OF WEST MERIDEN, CONNECTICUT, ASSIGNOR TO
THE MERIDEN BRITANNIA COMPANY, OF SAME PLACE.

Design No. 2,564, dated January 22, 1867.

DESIGN FOR A CASTER FRAME.

The Schedule referred to in these Letters Patent and making part of the same.

TO ALL WHOM IT MAY CONCERN:

Be it known that I, HORACE C. WILCOX, of West Meriden, county of New Haven, and State of Connecticut, have invented or produced a new and original Design for Caster Frames; and I do hereby declare that the following is a full and exact description thereof, reference being had to the photographic views, in which the same letters indicate like parts.

In the accompanying views are shown a new and original design for caster frames.

a are plain round bands, as the upper member of a frame; *c* is the plain caster spindle; *d* is a bead, as the middle member of the caster frame; *e* is a fillet, as the lower member of the caster frame, embellished with plain figured legs, *h*, the whole combined substantially in the manner shown and described to produce a plain, rich design for caster frames.

What I claim, and desire to secure by Letters Patent, is—

A design for caster frames, substantially as herein described and illustrated.

HORACE C. WILCOX. [L. S.]
